UNITED STATES PATENT OFFICE.

ALBERT POWELL, OF NEW BRITAIN, CONNECTICUT.

SPACER FOR PENDANT ELECTRIC LIGHTS.

1,307,923.

Specification of Letters Patent. Patented June 24, 1919.

Application filed October 29, 1918. Serial No. 260,120.

To all whom it may concern:

Be it known that I, ALBERT POWELL, a citizen of the United States, residing at New Britain, in the county of Hartford and State 5 of Connecticut, have invented new and useful Improvements in Spacers for Pendant Electric Lights, of which the following is a specification.

This invention relates to electric lighting 10 fixtures, particularly to attachments therefor, and has for its object the provision of a spacing member adapted to be used in connection with that type of electric lighting fixtures in which the lamp sockets and shades 15 are suspended by flexible members such as chains, my device being designed for the purpose of holding the different lamps and their shades in spaced relation to one another so as to prevent any possible swinging of 20 one shade against the other shades, an accident frequently occurring when reaching for the sockets in the dark and generally resulting in breakage of one or more of the shades.

An important object is the provision of a 25 device of this character which will be extremely simple and inexpensive in manufacture, which may be readily applied, which will be efficient in use, durable in service and a general improvement in the art.

With the above and other objects and advantages in view, the invention consists in 30 the details of construction to be hereinafter more fully described and claimed and illustrated in the accompanying drawing in 35 which:—

Figure 1 is a side elevation of my device applied to a plurality of pendent electric lights.

Fig. 2 is a plan view of my device the 40 light sockets being shown in diagrammatic sections.

Referring more particularly to the drawing the letter A designates an electric light fixture comprising a plurality of sockets B suspended from flexible members such as chains C. This is a well known and at present extremely popular style of fixture and is shown as illustrating the application of my

device which is designated as a whole by the letter D. 50

In carrying out my invention I provide a plurality of arms 5 which are simply lengths of wire of suitable size and material curved at their intermediate portions as shown at 6 and twisted together in pairs adjacent their 55 ends as shown at 7. The ends of each associated pair of arms 5 are arranged in divergent relation as shown at 8 to provide clamping members engageable about the sockets B. Each clamping member thus formed is of 60 substantially circular formation with a slightly constricted entrance opening 9. The extremities of the arms 5 are bent outwardly as shown at 10 to facilitate their engagement with the sockets B. 65

In use, the device is applied by engaging the ends of the arms with the sockets, whereupon the sockets will be maintained in proper spaced relation so that in case one socket is struck or otherwise swung it cannot 70 move in respect to the other sockets and the breaking of shade carried by the socket will be prevented.

While I have shown and described the preferred embodiment of the invention, it 75 will of course be readily understood that I reserve the right to make such changes in the form, construction and arrangement of parts as will not depart from the spirit of the invention nor the scope of the subjoined 80 claims.

Having thus described my invention I claim:—

1. In an electric lighting fixture, the combination with a plurality of flexibly suspended sockets, of a spacing member comprising a plurality of arms having their outer ends formed as resilient clamping members detachably engageable with said sockets for holding said sockets in spaced 85 relation. 90

2. In an electric lighting fixture, the combination with a plurality of flexibly suspended sockets, of a spacing member comprising a plurality of arms connected together in 95 pairs and having their outer ends curved

outwardly and bent inwardly to form clamping members engageable about said sockets for holding said sockets in spaced relation.

3. In an electric lighting fixture, the combination with a plurality of flexibly suspended sockets, of a spacing member comprising a plurality of arms formed as lengths of wire arranged in pairs and twisted together

adjacent their ends and having their end portions bent outwardly and then inwardly to provide clamping members engageable with said sockets for holding said sockets in spaced relation.

In testimony whereof I affix my signature.

ALBERT POWELL.

Copies of this patent may be obtained for five cents each, by addressing the "Commissioner of Patents, Washington, D. C."
